UNITED STATES PATENT OFFICE.

DICKRAN M. SARKISIAN, OF NEW YORK, N. Y.

TRAVERSE-RING.

No. 800,245.

Specification of Letters Patent.

Patented Sept. 26, 1905.

Application filed February 3, 1905. Serial No. 243,937.

To all whom it may concern:

Be it known that I, DICKRAN M. SARKISIAN, a citizen of the United States, and a resident of New York, county of New York, 5 State of New York, have invented an Improvement in Traverse-Rings, of which the following description, in connection with the accompanying drawings, is a specification, like numerals on the drawings representing like parts.

This invention has for its object the production of a novel, cheap, strong, and efficient traverse - ring especially adapted for use on curtain-poles to sustain thereon a curtain, portière, &c., and permit it to be readily drawn along the pole.

The various novel features of my invention will be fully described in the subjoined specification, and particularly in the claims 20 appended thereto.

Figure 1 is a side view of a traverse-ring embodying one form of my invention and mounted on a curtain - pole, shown in section. Fig. 2 is a detail thereof, the friction-rolls being omitted to show the character and location of the roll-supports. Fig. 3 is a side elevation of a form of friction-roll adapted for use in connection with my invention. Fig. 4 is a similar view, but showing the locking portion of the roll in position to retain it on the roll-support. Fig. 5 is a plan view, enlarged, of the blank from which the traverse-ring is formed, the opposite transverse slits having been made and showing the short tongues in readiness to be bent or rolled into tubular shape; and Fig. 6 is a transverse section taken on the line 6 6, Figs. 1 and 5, showing the flat blank in dotted lines.

In order to make a strong, light, and efficient traverse - ring which may be made cheaply and with comparative ease, I stamp, cut, or otherwise form a circular blank 1 from a sheet of metal of suitable character, such as brass, and I prefer to make the blank 45 continuous, as shown in Fig. 5. The width of the blank is such that when the same is bent or rolled to form a tubular body its two opposite edges will abut along the line 2, Figs. 1, 2, and 6, such line or joint being shown as 50 about midway between the periphery and the inner circumference of the completed ring.

By making the metal sufficiently stiff no soldering, brazing, or similar mode of uniting the lips is required.

Either at the time the blank 1 is formed or

subsequently I transversely slit the body oppositely from its inner and outer edges, as at 3 3 4 4, to leave two tongues 5 5 (see Fig. 5) oppositely extended from a connection 6, 60 which integrally unites the unslitted portions of the blank. The slits are made in oppositely-located pairs, as shown, and the tongues 5 are reduced in length for a purpose to be described, one or more slotted portions 65 being employed, according to the number of friction-rolls to be used.

Turning to Fig. 5, the tongues are first bent or rolled up into tubular form (see Figs. 2 and 6) of relatively small diameter to form 70 a roll-support 7. A short stiffening pin or rod 8 may then be forced into the tubular support, (see dotted lines, Figs. 1 and 2,) and in the drawings I have shown two of such supports. Now the broad portions of the 75 blank are bent or rolled into tubular form to present an annular tubular body having roll-receiving openings 9, Fig. 2, extended inward from the periphery of the body and each bridged by a tubular roll-support 7 integral with the body, the relative diameters of the support and the body of the ring being shown in Fig. 6. It will be manifest that the roll-support is eccentric to the longitudinal center of the ring, and in order to properly position the supports 7 for the friction-rolls to be referred to I push in or indent the body portion 1 at each end of the roll-support, as at 10, (see Figs. 1 and 2,) to bring the support somewhat nearer the longitudinal center of the body. Any suitable form of friction-roll is then applied—such as the split disk or roll 11, Figs. 3 and 4, having a central hole 12 and a radial slot 13, Fig. 3, adapted to be filled (after the roll-support 90 enters the hole 12) by a closing-block 14, Fig. 4, held in place in any suitable and permanent manner.

I prefer to provide the ring with two roll-receiving openings 9 and with two friction-rolls 14, as shown in Fig. 1, to travel upon the upper portion of the curtain-pole A; but my invention is not restricted to the number of rolls, as a single roll or a plurality of rolls may be used.

The roll is of greater diameter than the tubular body 1, and by locating the roll-support 7 as described the periphery of the roll projects inward beyond the inner circumference of the body, while the outer portion of the roll is substantially flush with the periphery of the body. This imparts a finish to the ring

and obviates any projecting parts outside of the ring to catch on the curtain or on other adjacent objects.

An eye 15 of any suitable construction is secured to the bottom of the ring, as shown in Fig. 1, to afford a means for connecting the curtain and ring.

Referring to Fig. 1, it will be seen that the joint 2 between the longitudinal edges of the body when the latter is bent or rolled into shape comes about midway of one side of the ring, and there is little tendency to open such joint, owing to the strength of the tubular form of the body and the stiffness of the metal. Consequently no soldering or brazing is necessary, and the same is true as regards the roll-support when bent into tubular form.

By varying the length of the tongues 5 the diameter of the roll-support is regulated, so that the support can be made larger or smaller, as desired.

My invention is not restricted to the precise construction and arrangement herein shown and described, as the same may be varied in different particulars by those skilled in the art without departing from the spirit and scope of my invention.

Having fully described my invention, what I claim as new, and desire to secure by Letters Patent, is—

1. A traverse-ring comprising a tubular, annular body having a transverse roll-receiving opening extended inward from its periphery and an integral roll-support of relatively small diameter bridging the opening adjacent the inner circumference of the body, and a friction-roll rotatably mounted on said support in the opening.

2. A traverse-ring comprising a tubular, annular body having a plurality of transverse roll-receiving openings extended inward from its periphery, and an integral roll-support of relatively small diameter bridging each opening adjacent the inner circumference of the body, and a friction-roll rotatably mounted on each support in the corresponding opening.

3. A traverse-ring comprising a continuous, annular tubular body transversely cut from its periphery inward to leave a roll-receiving opening, and having an integral, tubular roll-support of relatively small diameter bridging said opening adjacent the inner circumference of the body, and a friction-roll rotatably mounted on said support in the opening.

4. A traverse-ring comprising a tubular, annular body transversely cut from its periphery inward to leave a roll-receiving opening and having an integral neck bridging the

opening and bent into a tubular roll-support of relatively small diameter, and a split friction-roll rotatably mounted thereon in the opening.

65

5. A traverse-ring comprising a tubular, annular body, transversely cut from its periphery inward to leave a roll-receiving opening and an integral connection bridging the opening and presenting short oppositely-located tongues bent together to form a tubular roll-support of relatively small diameter, and a split friction-roll rotatably mounted thereon in the opening, the periphery of the roll projecting inward beyond the inner circumference of the body.

6. A traverse-ring comprising a tubular, annular body having a transverse roll-receiving opening extended inward from its periphery and an integral roll-support of relatively small diameter bridging the opening eccentric to the longitudinal center of the body, and a friction-roll rotatably mounted on said support in the opening and having its periphery projecting beyond the inner circumference of the body.

7. A traverse-ring comprising a one-piece tubular and continuous annular body having a plurality of transverse roll-receiving openings extended inward from its periphery and an integral, tubular roll-support of relatively small diameter bridging each opening eccentric to the longitudinal center of the body, and a friction-roll rotatably mounted on each support in the adjacent opening and having its periphery projecting beyond the inner circumference of the body.

8. A traverse-ring comprising a tubular, annular body having a transverse roll-receiving opening extended inward from its periphery and an integral roll-support of relatively small diameter bridging the opening eccentric to the longitudinal center of the body, a stiffening device for said support, and a friction-roll rotatably mounted on the latter in the opening.

9. A traverse-ring comprising a tubular, metallic annular body partially cut through transversely from its periphery to form roll-receiving openings and having tubular roll-supports integral therewith and bridging the openings, a stiffening-rod inserted in each roll-support, and friction-rolls rotatably mounted on said supports.

In testimony whereof I have signed my name to this specification in the presence of two subscribing witnesses.

DICKRAN M. SARKISIAN.
